(57) CLAIM

The ornamental design for a corn light, as shown and described.

DESCRIPTION

FIG. 1 is a front, right and top perspective view of a corn light, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

The broken lines shown in the drawings illustrate portions of the corn light that form no part of the claimed design.
